23 Claims. (Cl. 12—33.2)

1

This invention relates to shoe presses and particularly to those of the type used in repairing shoes.

Objects of the invention are to provide a convenient, simple and effective machine of this character which can be operated manually by an unskilled operator and by which uniform pressure may be applied to shoe bottoms in the cement attachment of soles to shoes of widely varying styles and sizes, the pressure so applied being substantially constant.

Characteristics of the machine are accessibility for inserting a shoe, prevention of damage to the shoe by excessive pressure, and capacity for movement of the shoe and last while under pressure to distribute the bottom pressure evenly.

The illustrated machine comprises a hollow shoe-bottom-pressing pad the top of which comprises a diaphragm of yielding material, the pad being filled with a liquid such as water at atmospheric pressure. The pad communicates with an open-topped water reservoir through an adjustable pressure-relief valve which may be set to open at a predetermined pressure. Thus, the pressure which can be applied to the sole of a shoe pressed upon the pad is limited to that to which the valve is set, and for a given setting the pressure applied to successive shoe bottoms will be substantially the same per unit of area.

In case more wrap is desired on the shoe bottom, some of the water may be allowed to pass into the reservoir so that the shoe will sink more deeply into the pad before the predetermined pressure is reached.

To permit the position of the shoe relatively to the pad to be changed while the shoe is under pressure to cause the pressure to be more evenly distributed on the shoe bottom, the machine includes a work-engaging abutment supported by a yoke which straddles the shoe and is pivoted on an axis extending transversely of the shoe located approximately in the plane of the pressing surface of the pad and substantially at the ball line of the shoe. Hence the operator may rock the yoke about its axis along with the shoe and last while under pressure to vary the distribution of pressure between the shoe and pad to meet varying conditions. Means is provided for locking the yoke in any position into which it may be rocked.

The axis or pivot of the yoke, which is spring biased to raised position, is movable heightwise of the last to press the abutment thereon, the yoke being connected by a linkage providing considerable mechanical advantage to a hand lever

2

which, after the abutment has been moved into engagement with the last, can be moved perpendicular to the pad to press the shoe against the pad, ratchet and pawl means being provided to hold the yoke depressed. To adapt the machine for use with lasts of different heights, the abutment is slidable heightwise with respect to the yoke, and a locking plate is provided to hold it from upward movement after it has been depressed to engage the last. Means is also provided for automatically unlocking the abutment when the yoke is raised upon release of pressure.

To facilitate removal of the shoe, means convenient for the operator is provided for tripping the relief valve to allow water to flow from the pad to the reservoir, thus releasing pressure on the shoe bottom. Tripping of this relief valve also energizes means for releasing a pawl holding the yoke down, the pawl being thus automatically released when the pressure on the shoe is lessened by flow of water to the reservoir.

Movement of the yoke toward the pad is utilized to close the relief valve before substantial pressure is applied to the shoe as well as to render the pawl operative to hold the yoke depressed.

To insure that the pad will contain its full quota of water before each pressing operation, spring-operated means is provided for raising the diaphragm when pressure thereon is removed and, in order that the flexibility of the diaphragm may not be reduced by too much upward pressure thereon, the spring is arranged to act through a toggle so that the more the diaphragm is depressed the less will be the pressure of the spring tending to raise the diaphragm, and vice versa.

These and other features of the invention will appear more fully from the following description when read in connection with the accompanying drawings and will be pointed out in the appended claims.

In the drawings,

Fig. 1 is a perspective view of the illustrated machine with a shoe in position and under pressure, the hand lever being broken away;

Fig. 2 is a right-hand side elevation of the machine, portions being broken away to show the internal mechanism;

Fig. 2a is an elevation of the left-hand ear on the base;

Fig. 3 is a plan view of the base of the illustrated machine, the pad and the water reservoir having been removed;

Fig. 4 is a section of the last-engaging abutment of the machine in depressed and locked position; and

Fig. 5 is a section of the water reservoir of the machine, the valve being closed.

The machine comprises a hollow metallic frame 10 adapted to be placed on a table or the like and being somewhat triangular in shape when looked at from above (Fig. 3), the base of the triangle being nearest to the operator. The sides of the frame upstanding from the base are flanged inwardly at the top, the upper faces of the flange presenting a face 12 (Fig. 2) inclined toward the operator at some fifteen degrees to the horizontal. An edge 14 (Fig. 3) of the flange defines a relatively large opening which is triangular in plan view, the front edge of the opening being coincident with the front edge of the base. An upstanding transverse rib 15 on the flange 12 adjacent to the rear end of the opening has formed in it from front to rear a substantially V-shaped recess 16 (Figs. 2 and 3). Formed on each side of the frame adjacent to the front edge are two upstanding ears 18, 20 (Fig. 1) in which are slots 22, 24 so inclined as to be substantially at right angles to the face 12. Extending inwardly from the ears 18, 20 (Fig. 3) are two projections 26 presenting upwardly wedge-shaped edges running transversely of the machine.

The wedge-shaped projection 26, together with the V-shaped recess 16, constitutes locating supports for a fluid-containing pad member having a resilient face against which a shoe bottom is to be pressed. The pad member comprises a metallic receptacle 28 (Figs. 1 and 2) of substantially horseshoe-shape in plan, open at its top and front, and adapted to contain a fluid, preferably water. Extending across the top and down the front portion of the receptacle is a diaphragm 30 of canvas-reinforced rubber held in position on an outwardly directed flange around the edges of the receptacle by an appropriately shaped clamping member 32 which is fastened to the flange by a series of screws and bolts 34.

Located inside the receptacle 28 (Fig. 2) is a distending means comprising a plate 36 slightly curved so as to conform approximately to the contour of the under side of the diaphragm 30 when in its distended condition, the plate being pivoted by means of a pin 38 passing through holes in two depending ears on the plate to an upper link 40 of a toggle. The lower link 42 of the toggle is pivotally connected at its upper end to the lower link 40 by a pin 44. A pin 46 carried by the lower end of the link 42 is journaled in a groove of an upstanding lug 48 on the bottom wall of the receptacle. Also pivotally connected to the pin 38 is a rearwardly extending link 50 the rear end of which is loosely held on an upstanding pin 52 driven into a boss formed on the bottom wall of the receptacle, the looseness of the link being to allow a certain amount of up-and-down movement of the link as the toggle tends to straighten under the influence of a tension spring 54 anchored between the pin 44 at the joint of the toggle and a depending lug 55 on the link 50. The action of the spring thus tends by means of the toggle to keep the diaphragm in a lightly distended condition. The arrangement is such that the spring and toggle have a greater mechanical advantage tending to distend the diaphragm when the diaphragm is most fully distended which advantage will gradually diminish as the diaphragm is depressed by the pressure of a shoe thereon.

The receptacle 28 and diaphragm 30, constituting a shoe-supporting pad, are of sufficient length to engage the bottom of a shoe of large size over the whole of its length in case it is desired to attach a full-length sole to the shoe. In case the operator wishes to attach a half sole to a shoe, the pad member 28, 30 may be moved bodily to a more rearward position on the frame so that only the sole portion of the shoe will be in contact with the diaphragm. For this purpose the receptacle 28 has formed along each side a depending rib 56 in which are provided a number of transverse notches 58 which, when in engagement with the wedge-shaped edges 26, serve to locate the pad fore and aft conveniently for the type of work being done. The receptacle also has a wedge-shaped rib 60 which has a sliding fit in the V-shaped recess 16 in the transverse rib 15 on the flange of the frame. Finger-holds 61 are provided on the lower front portion of the receptacle 28 to facilitate lifting and moving it longitudinally.

The rear end portion of the receptacle 28 extends considerably rearwardly of the diaphragm to form a circular face 62 (Fig. 2) so arranged as to support a water reservoir 64 attached thereto by screws, a water-tight joint being made by a washer 66 of resilient material. A hole having a frusto-conical seat 68 is provided in the bottom of the reservoir 64 in line with a duct 70 connecting a cavity of the receptacle to the reservoir. A vertical rod 72 (Fig. 5) carrying near its lower end a hemispherical washer 74 of resilient material acts as a shut-off and relief valve between the reservoir and the pad member and is operated as will be later explained. Also carried on the rod 72 is a baffle 76 which prevents water splashing through the opening at the top of the reservoir. A hollow projection 78 on the upper end portion of the water reservoir provides a funnel for filling the pad and the water reservoir to the desired depth.

Formed on the rear side of the hollow projection 78 are two lugs 80 (Fig. 5) in which is carried a pin 82, which pin serves as a pivot for a valve-operating lever 84 which, about half way of its length, is pivoted to the upper end of the valve rod 72. The rear end of the valve-operating lever is provided with a hole through which passes a nearly vertical rod 86 on the upper portion of which is threaded a washer 88 and a coil spring 90 retained against upward movement by an adjustable collar 92, the washer being interposed between the lower end of the spring and the upper face of the valve-operating lever 84. A second collar 94 fixed on the rod just below the valve-operating lever engages a lower face thereof. The rod 86 passes down behind the reservoir (Fig. 2), the lower end of the rod being pivotally connected to the rear portion of a plate-like lever 96 the forward end of which is pivoted on a pin 98 which passes transversely through the rear upper portion of the frame.

The lever 96 is provided below its pivot with a cam slot 100 which engages a cam roll 102 rotatably mounted on a pivot 104 extending transversely of the upper end of a trip lever 106. The trip lever is pivoted near its lower end on a pin 108 passing transversely through the rear lower portion of the frame. The pin 104 of the cam roll is extended to provide a pivotal connection to a trip rod 110 which extends forwardly through the frame and projects at the front where it carries a knob 112 in position to be actuated by

the operator's left hand. Thus, when the knob 112 is pushed rearwardly by the operator, the cam roll 102 carried by the trip lever 106, moves rearwardly in a circular path about the pivot 108. The first part of the cam slot 100 is inclined to the path of the roll 102 so that the lever is moved upwardly about its pivot 98, the roll then passing into a portion of the slot which is concentric with the path of the roll. This causes the rod 86 to be moved upwardly so that the lower collar 94 will engage the under side of the valve-operating lever 84 and raise the rod 72, causing the resilient washer 74 to be raised out of engagement with the seat 68 of the hole in the bottom of the reservoir and held up. The rod 72 is thus raised when the operator wishes to remove a shoe from the apparatus at the conclusion of a bottom-pressing operation.

Means is provided (Fig. 1) for pressing the shoe firmly down on the diaphragm 30, said means comprising a pressure-applying and distributing yoke 114 of inverted Y-shape having limbs 115, 116 which straddle the pad. The upper portion of the yoke 114 (Fig. 4) is bored vertically to form a bearing for a sliding shaft 117 on the upper end of which is attached a handle member 118. The lower end of the sliding shaft 117 is rounded at the lower end to form an abutment 119 for engaging the pressure-receiving portion P of a last L (Fig. 1) overlying the forepart of the sole of a shoe to be operated on. Side flanges 120 (Fig. 4) are also provided to engage the sides of the pressure-receiving portion P of the last. The sliding shaft 117 is splined at 122 to the yoke 114 to prevent rotation while allowing longitudinal movement of the shaft. The shaft 117 is urged upwardly by a lever 124 pivoted on a pin 126 carried by the yoke, one end of the lever engaging the lower rear edge of the handle member 118 while the other end is connected to a spring 128 anchored to the yoke. The upper portion of the sliding shaft 117 is shrouded forwardly and rearwardly by the downwardly extending flanges of the handle 118 and passes through a hole provided in a locking bar 130 (Fig. 4) pivotally supported between two links 132 on a pin 134 which is journaled in the upper portions of the links. The links are pivotally supported at their lower ends on another pin 136 which is carried by the yoke 114, the links being clamped together by a screw 138 passing through the front link and threaded into the rear link so that they form a single unit, a spacing collar 140 surrounding the screw 138 being located between the links 132 so they are free to move on their pivot 136. A hole larger than the spacing collar 140 is provided in the yoke 114, through which hole the screw 138 and the collar 140 pass to allow a limited amount of movement of the link unit. The locking bar 130 is urged upwardly by a spring 142 housed in the yoke 114. An extension 144 of the locking bar 130 is adjustably connected to a downwardly extending rod 146 which passes through an opening provided in the left limb 116 of the yoke (Fig. 1) and is pivotally connected at its lower end to a lever 148 (Fig. 2a). The lever is pivoted at its rear end on a pin 150 carried in a rearward projection of a left side link 152 which is pivoted to the limb 116 of the yoke. The lever 148 (Fig. 1) is provided with a lateral extension 154 which underlies a lug 156 on the ear 18 of the base. The arrangement is such that when the yoke is in its upper position the lever 148 is held by the lug 156 on the ear 18 in such a position

that the locking bar 130 is horizontal, in which position the sliding shaft 117 can slide smoothly through the hole in the locking bar. When the yoke is moved down, however, the extension 154 is no longer in contact with the lug 156 and the locking bar 130 is free to be tilted in a clockwise direction by the spring 142 about the pivot 134 to lock the shaft 117 against upward movement.

The limbs 115, 116 of the yoke 114 are each bifurcated, one to engage the left link 152 and the other to engage a right link 157, the links controlling the heightwise position of the yoke. The upper end of each link is pivoted on a transverse pin 158 of such length that it extends outwardly beyond the limb of the yoke and carries a roll 160 freely mounted thereon and located one in the slot 22 of the ear 18 and the other in the slot 24 of the ear 20, the rolls 160 being coaxial. The limb 115 of the yoke has a rearward extension 161 (Fig. 2) and when not in use is swung rearwardly by a tension spring 162 connected at one end to a pin 163 on the extension 161 rearwardly of the pin 158 and the other end to the frame, the yoke being thus biased to the rearwardly swung position shown in Fig. 2 with a face of the extension 161 in contact with a pin 164 on the link 157. The yoke 114 is free to be swung about the axis of the pins 158 and is of such an overall width as to be able to move freely between the upwardly extending ears 18, 20 of the frame, the cam rolls 160 engaging the inclined slots 22, 24 therein.

The right-hand limb 115 (Fig. 2) of the pressure-distributing yoke 114 is extended downwardly to form a toothed segment 166 concentric with the pivot pins 158 on which the yoke is mounted. A latch 168 frictionally pivoted to the link 157 by a pin 170 is provided to engage the teeth of the segment so that when the pressure-distributing yoke is moved about its pivots it may be latched in the desired position. A pin 172 projecting from the side of the latch serves by contact with a boss 174 on the frame to disengage the latch 168 from the segment 166 when the yoke rises on the release of pressure.

The lower ends of the two downwardly extending links 152, 157 are pivotally supported in bifurcated forward ends of two arms of a forked pressure-locking lever 176 (Figs. 2 and 3) which is supported approximately a quarter of the way along its length on coaxial pivots 178, 180 carried transversely in the frame.

Rearwardly converging arms of the pressure-locking lever 176 combine to support a transverse pivot 182 for the lower end of an upwardly extending link 184 and also to carry an upwardly extending ratchet segment 186 with which at appropriate times in the operation of the apparatus a locking pawl 188 is brought into engagement. The pawl is pivoted on a pin 190 supported by and extending transversely of the rear portion of the frame. The pawl is provided with a spring finger 192 by which it is moved into and out of engagement with the segment 186. For this purpose the upper end portion of the spring finger engages a slot provided in the lever 96 above mentioned.

When the trip rod 110 is pushed rearwardly by the operator, the cam roll 102 carried by the trip lever 106 moves in the cam slot 100 in the lever 96, causing said lever to swing counterclockwise about its pivot until the roll reaches the end portion of the cam track, which end portion is so shaped that it effects no further movement of the lever 96 during movement of the

cam roll therealong but causes the lever 96 to remain stationary in its elevated position. The initial movement of the lever 96 opens the valve, and not until the valve is opened does the pawl 188 become disengaged by the action of the lever 96 on the spring finger 192 to free the pressure-locking lever.

When the pawl is disengaged, the yoke moves upwardly and the rear end portion of the pressure-locking lever 176 moves downwardly until an extension of the pin 182 engages a forward extension 194 of a downwardly extending arm of the trip lever 106 which it depresses until further movement is prevented by contact of a projection 196 of the trip lever with a stop roll 198 mounted on the pressure-locking lever 176. The depression of the forward extension 194 of the trip lever causes the cam roll 102 carried by the opposite end of the trip lever to move out of the "rest" position in the cam slot of the lever 96 into a position where a spring 200 anchored between the lever 96 and the projection 196 of the lever 106 tends to urge the lever 96 downwardly and would do so were it not now prevented by the contact of the trip lever projection 196 with the stop roll 198. The position of the lever is now such that the valve is open and the pawl 188 is disengaged, although, during the first part of the next upward movement of the pressure-locking lever 176, the valve will be closed and the locking pawl will be re-engaged by the reaction of the tension spring 200 when permitted to do so by movement of the roll 198 above the projection 196. When the operator wishes to remove a shoe from the apparatus after attachment of the sole thereto, he will push the knob 112 and the trip rod 110 rearwardly to open the valve so that water may flow from below the diaphragm into the reservoir under the pressure of the shoe against it.

Rearward movement of the trip rod 110 will also serve to disengage the locking pawl 188 from the locking segment 186, thus releasing the yoke for upward movement away from the shoe. The opening of the valve will, however, precede the disengagement of the locking pawl by such a time interval as will insure that the water pressure beneath the diaphragm will have been falling considerably before the yoke is free to rise. This is the reason for the introduction of the spring finger 192 which yields under the pressure of the lever 96 until the pressure between the segment 186 and the pawl 188 is very much reduced. Then, and then only, is the tension of the spring finger able to move the pawl out of engagement with the segment. This fact prevents the yoke from being forcibly jerked upwardly on release of the locking pawl.

The upper end of the upwardly extending link 194, which is pivoted at its lower end at 182 to the pressure-locking lever, is pivotally connected at 201 to a relatively short, rearwardly extending, bifurcated arm 202 of a hand lever 204 mounted on a pivot 206 having a bearing in a boss 207 extending transversely of the frame. The distance between the pivot 206 and the forward end of the hand lever is about five times that between the pivot 206 and the pivot 201 on the rear end of the lever. The hand lever extends forwardly and upwardly from the pivot 206 when the machine is ready to receive a shoe, terminating in a handle near the front of the machine conveniently to be operated by the right hand of the operator to lower the yoke and cause the shoe to be thrust against the di-

aphragm. A spring 208 interconnecting the hand lever and a fixed hook serves to restore the hand lever and the parts connected thereto to their initial positions on release of the locking pawl 188.

The under side of the receptacle is provided with a cavity 210 immediately adjacent to the water-containing compartment which closely envelops an electrical heating element 212, the element serving to heat the water in the pad member. A heat-regulating switch 214 is also provided conveniently placed at the front of the apparatus which enables the water to be kept approximately at a predetermined temperature.

In the operation of the apparatus, the heat-adjusting switch 214 will have been previously set for the desired heat and sufficient time allowed for the water to have reached the desired temperature. The operator will then take a shoe with a cemented sole in position and insert in the shoe the last L having the pressure-receiving portion P overlying the forepart of the shoe and preferably of the type described in United States Letters Patent No. 2,126,941, granted August 16, 1938, upon application of George H. Barge.

He will then place the shoe and last in the apparatus so that the sole is in contact with the diaphragm and approximately centrally laterally under the pressure-distributing yoke, the pad member having already been located on a selected pair of notches 58 which insure that the whole of the area to be pressed overlies a suitable portion of the diaphragm. With his left hand the operator will then depress the handle member 118 until the abutment 119 is located on the notch in the pressure-receiving portion P of the last. With his right hand the operator will then move the hand lever 204 forwardly and downwardly, thus causing its short rearwardly extending arm 202 to move upwardly which, by means of its connecting link 194, raises the rear end of the pressure-locking lever 176. Release of the lever 106 by upward movement of the roll 198 allows the spring 200 to move the plate-like lever 96 to close the relief valve and tensions the spring finger 192 toward the pawl 188 to hold it against the ratchet segment 186 and prevent downward movement thereof. The forward end of the lever 176 moves downwardly, together with the links 152, 157 which carry down the rolls 186 in the slots 22, 24 in the ears 18, 20 of the base, and consequently the limbs of the yoke move downwardly. The first part of the downward movement of the yoke and the link 152 causes the extension 154 of the lever 148 to be lowered out of engagement with the lug 158, thus permitting the spring 142 to tip the locking plate 130 to lock the sliding shaft 117 to withstand the upward pressure of the diaphragm. The shoe is thus urged down against the resilient resistance of the water-filled pad member the diaphragm of which yields and conforms to the shoe bottom until it presses the sole into complete contact with the shoe bottom.

If it is now observed that some portion of the shoe is pressed more deeply into the diaphragm than other portions, indicating a variation in the pressure with which different parts of the sole are being pressed against the shoe bottom, the yoke 114 may be rocked forwardly or rearwardly about the pins 158 which then lie substantially in the plane of the diaphragm and the yoke held in the desired position by moving the latch 158 into engagement with the segment 186. It will

also be understood that if successive shoes of a pair are placed in somewhat differing positions on the pad to be pressed thereagainst by descent of the yoke, the fact that the heightwise contour of the shoe bottom and the pad differ from each other will be likely to cause the two shoes to sink into the diaphragm in differing manners with consequent inconsistency in the pressure exerted against their bottoms. If the operator should observe, for some such reason as above given, that a particular shoe is not being thrust against the pad by the abutment 119 in the manner he considers most desirable, he can, in spite of the fact that the abutment is bearing firmly against the last within the shoe, rock the yoke about its pivot pins 158, thereby moving the point of engagement of the abutment with the last also about these pins, thus causing the shoe to be tilted on the diaphragm to an extent sufficient to cause the parts of the shoe bottom to sink into the diaphragm to the desired extent. The fact that when the shoe is being pressed against the pad the pins 158 about which the yoke swings are more or less on the same level as the diaphragm 30 facilitates the rocking of the shoe and reduces any tendency for it to be moved forwardly or rearwardly upon the pad by the swinging of the yoke. The ability of the operator thus to modify the pressure applied to different portions of the shoe bottom even while the shoe is under pressure constitutes an unusual advantage over shoe-bottom-pressing devices commonly available since, when using such devices, it is customarily necessary to release the pressure on the shoe and reposition it on the shoe-bottom-pressing pad or to readjust the shoe-pressing abutment if it is noticed that a shoe is being pressed against its pad in an undesired manner.

Having thus described my invention, what I claim as new and desire to secure by Letters Patent of the United States is:

1. A shoe press having, in combination, a pad containing liquid, a valve controlling exit of liquid from the pad, means for applying pressure to a shoe located on the pad, manually operated means for opening the valve at the conclusion of a pressing operation on a shoe, and means rendered operative by the initial movement of the pressure applying means toward the pad for closing the valve.

2. A shoe press having, in combination, a pad containing liquid, a reservoir open to the atmosphere connected with the pad, a valve seat between the pad and the reservoir, a resilient valve engaging said seat, a spring for holding the valve against its seat, means for varying the tension of the spring, and manually operated means for pressing a shoe against the pad with a pressure determined by the tension of the spring.

3. A shoe press having, in combination, a pad containing liquid, a reservoir connected to the pad, a valve between the pad and the reservoir, means for applying pressure to a shoe located on the pad, manually operated means for opening the valve at the conclusion of a pressing operation on a shoe, and means rendered operative by the initial movement of the pressure-applying means toward the pad for closing the valve.

4. A shoe press having, in combination, a pad, a yoke straddling the pad, an abutment movable heightwise of the yoke to engage a last on the pad, a locking plate through which the abutment extends, a spring tending to tilt the plate and

lock the abutment against movement away from the pad, and means for moving the yoke heightwise of the last to press the shoe and last toward the pad, said movement of the yoke permitting the spring to tilt the locking plate to prevent upward movement of the abutment.

5. A shoe press having, in combination, a pad, a yoke straddling the pad, an abutment movable heightwise of the yoke to engage a last on the pad, a locking plate through which the abutment extends, a spring tending to tilt the plate and lock the abutment against movement away from the pad, and means for moving the yoke heightwise of the last to press the shoe and last toward the pad, upward movement of the yoke acting to move the locking plate to inoperative position.

20 6. A shoe press having, in combination, a pad, a yoke straddling the pad, means for guiding the yoke in a direction perpendicular to the pressing face of the pad to apply pressure to a last and shoe, said yoke being mounted on an axis extending transversely of the pad and substantially in the plane of the pressing face of the pad when in pressure-applying position, and means for operating the yoke to press the shoe upon the pad.

30 7. A shoe press having, in combination, a pad, a yoke mounted for movement on an axis extending transversely of the pad, means guiding said axis for movement perpendicular to the pad surface, and means for moving the yoke downwardly to apply pressure to the shoe on the pad, such movement disposing the axis substantially in the plane of the pressing surface of the pad, the yoke being movable about said axis to alter the pressing relation between the pad surface and the shoe bottom.

35 8. A shoe press having, in combination, a yielding pad, a yoke straddling the pad, the yoke being mounted to swing lengthwise of the shoe about an axis extending transversely of the pad, means for moving the yoke heightwise to apply pressure to a last and shoe on the pad, the yoke being swingable about said axis while the last and shoe are under pressure evenly to distribute the pressure applied to the shoe bottom, and means for holding the yoke in the position to which it is swung.

40 9. A shoe press having, in combination, a pad, a yoke mounted for movement on an axis extending transversely of the pad, means guiding said axis for movement perpendicular to the pad surface, means for moving the yoke downwardly to apply pressure to the shoe on the pad, such movement disposing the axis substantially in the plane of the pressing surface of the pad, the yoke being movable about said axis to alter the pressing relation between the pad surface and the shoe bottom, a toothed segment on the yoke, and a latch for engaging the segment.

45 10. A shoe press having, in combination, a pad, a yoke mounted for movement on an axis extending transversely of the pad, means guiding said axis for movement perpendicular to the pad surface, means for moving the yoke downwardly to apply pressure to the shoe on the pad, such movement disposing the axis substantially in the plane of the pressing surface of the pad, the yoke being movable about said axis to alter the pressing relation between the pad surface and the shoe bottom, a toothed segment on the yoke, a latch for engaging the toothed segment, and means operated by upward movement of the yoke for releasing the latch.

11

11. A shoe press having, in combination, a liquid-containing pad having a resilient diaphragm forming the pressing surface of the pad, a reservoir connected with the pad, a pressure-relief valve between the pad and the reservoir, means for pressing a shoe against the diaphragm, the pressure so applied being limited by opening of the relief valve, a plate inside the pad movable toward the diaphragm to dilate the pad when pressure thereon is released, a toggle engaging the plate and so arranged that straightening of the toggle moves the plate toward the diaphragm, and a tension spring connected to the pivot of the toggle whereby the more the diaphragm is depressed by pressure of the shoe thereon the less the dilating effect of the spring.

12. A shoe press having, in combination, a pad containing liquid, a reservoir open to the atmosphere connected with a pad, a valve seat between the pad and the reservoir, a resilient valve engaging said seat, a spring for holding the valve against its seat, means for varying the tension of the spring, means for pressing a shoe against the pad with a pressure determined by the tension of the spring, and means including a spring and toggle for dilating the pad when the pressure thereon is released so arranged that the greater the dilation the greater the dilating pressure of the spring.

13. A shoe press having, in combination, a pad containing liquid, a reservoir connected with the pad, a valve between the pad and the reservoir, means for applying pressure to a shoe on the pad including a lever, and means rendered operative by movement of said lever in pressure-applying direction for seating the valve.

14. A shoe press having, in combination, a pad containing liquid, a reservoir connected with the pad, a valve between the pad and the reservoir, means for applying pressure to a shoe on the pad including a pressure-locking lever, a valve lever for opening and closing said valve, and means biasing the valve lever to valve-closing position, movement of said pressure-locking lever in pressure-applying direction permitting operation of the valve lever to close the valve.

15. A shoe press having, in combination, a pad containing liquid, a reservoir connected with the pad, a valve between the pad and the reservoir, means for applying pressure to a shoe on the pad including a lever, means for opening the valve while the shoe is under pressure and holding it open, a spring tending to close the valve, and means operated by movement of the pressure-applying lever to pressing position for rendering said spring effective to close the valve.

16. A shoe press having, in combination, a pad containing liquid, a reservoir connected with the pad, a valve between the pad and the reservoir, means engaging a last to press the last and shoe upon the pad, a valve-operating lever movement of which in one direction seats the valve and movement of which in the other direction unseats the valve, a tripping lever connected to the valve-operating lever to move it in either direction, part of the movement of the tripping lever being neutral and imparting no movement to the valve-operating lever, and means effective on movement of the last-engaging means away from the shoe to move the tripping lever out of neutral position.

17. A shoe press having, in combination, a liquid-containing pad, a reservoir connected with the pad, a valve between the reservoir and the pad, means for pressing a last and shoe on the

12

pad including a pressure-locking lever having a toothed segment, a plate-like lever connected to the valve and having a slot therein, and a tripping lever engaging the slot in the plate-like lever and having an active and a neutral position in said slot, operation of the tripping lever moving the plate-like lever in a direction to open the valve before entering its neutral position, movement of the pressure-locking lever to released position engaging the tripping lever to move it out of neutral position.

18. A shoe press having, in combination, a pad containing liquid, a reservoir connected with the pad, a valve between the pad and the reservoir, means engaging a last to press the last and shoe upon the pad, a tripping lever, a lever having a slot part of which is concentric with the pivot of the tripping lever, a roll on the tripping lever engaging said slot, movement of the slotted lever in one direction seating the valve and movement in the other direction unseating the valve, a spring tending to move the slotted lever to valve-seating position, means for moving the tripping lever to unseat the valve and move the roll thereon into the concentric part of the slot rendering the spring inoperative to seat the valve, and means controlled by the last-engaging means to move the roll out of the concentric part of the slot to permit the spring to act.

19. A shoe press having, in combination, a pad containing liquid, a reservoir connected with the pad, a valve between the pad and the reservoir, means engaging a last to press the last and shoe upon the pad, a pressure-locking lever connected to the last-engaging means, a ratchet on the locking lever, a pawl on a fixed axis for holding the pressure-locking lever in pressure position, means for closing the valve, and means operated by the valve-closing means for rendering the pawl effective to engage the ratchet on the pressure-locking lever.

20. A shoe press having, in combination, a pad containing liquid, a reservoir connected with the pad, a valve between the pad and the reservoir, means engaging a last to press the last and shoe upon the pad, a pressure-locking lever connected to the last-engaging means, a ratchet on said lever, a pawl on a fixed axis for holding the pressure-locking lever in pressure-applying position, means for closing the valve, and means operated by the valve-closing means for rendering the pawl effective to hold the pressure-locking lever.

21. A shoe press having, in combination, a pad containing liquid, a reservoir connected with the pad, a valve between the pad and the reservoir, means engaging a last to press the last and shoe upon the pad, a slotted lever movement of which in one direction seats the valve and movement of which in the other direction unseats the valve, a tripping lever carrying a roll engaging the slot in the slotted lever, and a trip rod connected to the trip lever for moving the slotted lever to unseat the valve.

22. A shoe press having, in combination, a liquid-containing pad, a reservoir connected with the pad, a valve between the reservoir and the pad, means for pressing a last and shoe on the pad including a pressure-locking lever having a toothed segment, a valve lever connected to the valve and operable to open and close it, a pawl on a fixed axis for engaging the toothed segment, and a spring finger on the pawl engaging the valve lever, movement of the valve lever to open the valve stressing the finger in a direction away

13

from the segment and movement of the valve lever to close the valve stressing the finger in a direction toward the segment.

23. A shoe press having, in combination, a liquid-containing pad, a reservoir connected with the pad, a valve between the reservoir and the pad, means for pressing a last and shoe on the pad including a pressure-locking lever having a toothed segment, a plate-like lever connected to the valve and having a slot therein, a tripping lever carrying a roll engaging the slot in the plate-like lever, a trip rod for operating the tripping lever, a pawl on a fixed axis for engaging the toothed segment, and a spring finger on the pawl engaging the plate-like lever, operation of

5

14

the tripping lever by the trip rod moving the plate-like lever in a direction to open the valve and to stress the finger in a direction to move the pawl away from the segment.
